(57) **CLAIM**

The ornamental design for a fishing buoy marker, as shown and described.

DESCRIPTION

FIG. 1. is a perspective view of a fishing buoy marker, showing our new design;

FIG. 2. is another perspective view of FIG. 1 thereof;

FIG. 3. is a front elevation view of FIG. 1 thereof, with the rear elevation view being a mirror image thereof;

FIG. 4. is a top plan view of FIG. 1 thereof, with the bottom plan view being a mirror image thereof;

FIG. 5. is a right side elevation view of FIG. 1 thereof, with the left side elevation view being a mirror image thereof;

FIG. 6. is an exploded perspective view of a fishing buoy marker;

FIG. 7. is another exploded perspective view of FIG. 6 thereof;

FIG. 8. is a front elevation view of FIG. 6 thereof;

FIG. 9. is a rear elevation view of FIG. 6 thereof;

FIG. 10. is a top plan view of FIG. 6 thereof;

FIG. 11. is a bottom plan view of FIG. 6 thereof;

FIG. 12. is a right side elevation view of FIG. 6 thereof;

FIG. 13. is a left side elevation view of FIG. 6 thereof; and,

FIG. 14. is another perspective view of FIG. 1 thereof, with the fishing buoy marker in a configuration of use with unclaimed environment.

The broken lines in FIG. 6-13 depict portions of a fishing buoy marker and form no part of the claimed design.

The broken lines in FIG. 14 depict environmental subject matter that forms no part of the claimed design.

1 Claim, 9 Drawing Sheets
